US0D1067949S

(12) **United States Design Patent** (10) Patent No.: **US D1,067,949 S**
(45) Date of Patent: ** Mar. 25, 2025

(54) **REFRIGERATOR**

(71) Applicant: **LG ELECTRONICS INC.**, Seoul (KR)

(72) Inventors: **Seunghyun Ji**, Seoul (KR); **Dongeun Kim**, Seoul (KR)

(73) Assignee: **LG ELECTRONICS INC.**, Seoul (KR)

(**) Term: **15 Years**

(21) Appl. No.: **35/520,292**

(22) Filed: **Mar. 15, 2023**

(80) **Hague Agreement Data**

Int. Filing Date: **Mar. 15, 2023**

Int. Reg. No.: **DM/227982**

Int. Reg. Date: **Mar. 15, 2023**

Int. Reg. Pub. Date: **Mar. 15, 2024**

(30) **Foreign Application Priority Data**

Sep. 27, 2022 (KR) 30-2022-0039609

(51) **LOC (15) Cl.** **15-07**

(52) **U.S. Cl.**

USPC **D15/79**

(58) **Field of Classification Search**

(57) **CLAIM**

The ornamental design for a refrigerator as shown and described.

DESCRIPTION

1. Refrigerator

1.1 : Perspective

1.2 : Front

1.3 : Back

1.4 : Left

1.5 : Right

1.6 : Top

1.7 : Bottom

1.8 : Reference

1.9 : Reference

The broken lines depict a portion of the article that form no part of the claimed design; the claimed design is a modular table-type refrigerator and its composition or layout of the modular can be changed for the convenience of users; reproduction 1.8 is a reference view showing the state that the table top is removed and the refrigerator can be arranged as on top of each other; reproduction 1.9 is a reference view showing the state that the water reservoir is separated and the drawer of the modular is opened; reproductions 1.8 and 1.9 form no part of the claimed design.
